RING TRAVELER

James McD. McLeod, Bishopville, S. C., assignor
to Victor Ring Traveler Company, a corpora-
tion of Rhode Island

Application April 17, 1934, Serial No. 720,959

12 Claims. (Cl. 118—61)

This invention relates to a ring traveler for spinning and twisting frames; and has for one of its objects the provision of a traveler which may be more easily applied to a ring by reason of its 5 construction than travelers of the usual construction, which have heretofore been made.

Another object of the invention is the provision of a traveler which although being provided with means to allow it to be more easily placed upon 10 the ring, will not change its weight and therefore not change its running position on the ring.

Another object of the invention is the provision of a traveler which will not load or acquire lint accumulation which changes the running qualities 15 of the traveler on the ring.

Another object of the invention is the provision of means which act not only to permit the traveler to be more easily placed on the ring, but also has the additional property of reducing the lint 20 accumulation or load of the ring.

A further object of the invention is the provision of a traveler so constructed that it may be made readily by machine operations and without reducing the strength of the traveler.

25 A still further object of the invention is the provision of a means which will reduce the breakage of the travelers when applied to the ring by causing them to be more flexible and easily applied.

30 With these and other objects in view, the invention consists of certain novel features of construction, as will be more fully described and particularly pointed out in the appended claims.

In the accompanying drawing:

35 Fig. 1 is a side elevation of the traveler showing the ring in section and the position of the traveler on the ring while running.

Fig. 2 is a similar view of the ring and illustrates the traveler in dotted lines in its normal 40 position, and in full lines with the opening between the horns increased by reason of its being forced over the flange of the ring.

Fig. 3 is a top plan view of the traveler.

Fig. 4 is a side elevation of the traveler of a 45 modified construction.

Fig. 5 is a side elevation of a traveler of a slightly different construction.

Fig. 6 is a plan view of the traveler shown in Figure 5.

50 Fig. 7 is a perspective view of the traveler shown in Figures 1, 2 and 3.

Fig. 8 is a side elevation of a twisting traveler or traveler of the vertical type and different in this respect from the horizontal type heretofore 55 illustrated.

Fig. 9 is a plan view of the back of the traveler shown in Figure 8.

Fig. 10 is a side elevation of a modified shape of traveler, and

Fig. 11 is a top plan view of the shape of traveler shown in Fig. 10.

Ring travelers used in spinning and twisting are found to be a very important element in obtaining the quality of yarn desired, and an important element with reference to the breakage 10 of the yarn, or as it is frequently termed in spinning language "keeping the ends up", particularly at the very high rates of speed which are being used in spinning at the present time. Many of these travelers in spinning acquire a rate 15 of over a mile a minute and travelers when made of sufficient hardness to withstand the use to which they are put are often difficult to spring over the flange of the ring by spreading the horns and sometimes in placing them in position the 20 traveler will break; and in order to avoid these undesirable results, I have provided a traveler which is more flexible at a suitable point desired to enable it to be more readily positioned on the ring and without breakage to the traveler; and 25

I have accomplished this without reducing the stock of the traveler, and thus I have not changed its weight or running properties by spreading out the stock to make it thinner and more flexible at one point, and I have also acquired a further and 30 more desirable advantage which is that of preventing loading to a material extent of the traveler and one which will have less end breakage by reason of this construction than travelers heretofore made; and the following is a more detailed 35 description of the present embodiment of this invention, illustrating the preferred means by which these advantageous results are accomplished.

With reference to the drawing, 10 designates 40 the ring having an upper flange 11 and lower flange 12; these flanges being interchangeable by turning the ring over.

The traveler is designated 14 and consists of horns 15 and 16 connected by a shank or bow portion 17 on a generally continuous curvature, and formed over an arbor in the usual manner to acquire this curvature and shape desired. This traveler will run with substantially a single point of contact at the inner edge of the ring, such as 45 50 at the point 18, as illustrated in Figure 1, the yarn 19 being shown as passing through the traveler to be guided about the bobbin as it comes from the rolls.

The distance between the horns 15 and 16 is of 55

such extent as to require these horns to spread apart as the traveler is being forced over the flange of the ring. In Figure 2, the traveler 14 is shown in dotted lines in its normal position as being applied to the ring and showing the relation of the distance between the horns to the flange, while in full lines, I have illustrated the traveler as sprung open to increase the distance between the horns that it may pass over the flange of the ring, and in order that this spreading of the horns may more readily take place and the pressure required to force the traveler onto the ring lessened, I have thinned the stock as at 20, at a point substantially the middle of the traveler, as illustrated, so as to preserve the balance of the traveler regardless of whether the horn 15 is on the outer or inner web of the ring.

This thinning or flattening of the stock is caused by striking the traveler and with a hammer like blow during its formation which causes the stock to be squashed down or squeezed out and thinned, as illustrated in the drawing, see Figures 1, 2, 3 and 7, and at the same time the stock spreads out to provide protruding portions 21 and 22 on either side of the traveler which I control to provide the proper shape of spread by the shape of the tool used to transmit the pressure required, and while I choose to form this traveler by striking it on the inner surface, as illustrated in Figures 1, 2, 3 and 7, I may also strike the traveler on the outside to preserve the curvature on the inner surface 23 and thus flatten out the outer surface as at 24, as illustrated in Figure 4, or in addition to providing a single thinned portion, I may strike this traveler at other points such as 25 and 26 on either side of the center thinned portion in Figure 6, so as to provide a plurality of points of bending where desired, or as illustrated in Figures 8 and 9, this flattening may occur either at the points 30, 31 or 32, or at all three points if desired on the vertical traveler.

The flattening or spreading of the stock in this manner maintains the same amount of stock as would be maintained in a traveler having a wire of regular or uniform size throughout its length, but spreads this stock in a different shape, yet I have a traveler in which every right angular cross section taken through the traveler or wire 50 will have the same sectional area, regardless of where the sections are taken, and by this arrangement I maintain the weight of the traveler substantially the same as it was before, so that the horizontal neutral axis and center of gravity 55 are not disturbed and yet a traveler is provided which by reason of its shape will permit of greater resiliency or flexibility at these points where the change in shape occurs.

This shaping also has the further advantage 60 of reducing the loading of the traveler. As the yarn 19 runs through the traveler (see Figure 1) there are at times small particles of fibers scraped off of the yarn, and while usually these particles are blown or fly off, at times, the twist of fibers 65 or for some other reason they embrace the traveler lodging thereon about the traveler and do not dislodge by the air blowing across, and when so gripping the traveler the particles through centrifugal force travel from the inside where the 70 yarn engages to the opposite outside bend of the traveler and there accumulate to form what is known as loading, and I have found that by spreading the stock of the traveler at a point along the traveler over which these fibers must 75 pass that these fibers will be spread out in a wider

form and be blown from the traveler and that loading is thus in many instances prevented and is materially decreased. I further find that in running a traveler of this character, there are fewer ends down, that is, there are fewer breakages, than with a traveler of the usual construction, and which I attribute partly to the prevention of loading.

In the operation of this traveler, it is frequently found that the yarn will traverse back and forth along the traveler to a certain extent, and I find that by the provision of this broadened portion 20 of the traveler that I may control or localize this traverse and reduce the extent thereof.

I have also illustrated in Figures 10 and 11 at 40, a differently shaped traveler and have also shown the flattened portion 41 as provided herein to permit of the advantageous results being obtained as above specified.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A ring traveler comprising horns, a shank portion connecting said horns, said traveler having substantially the same amount of metal at any right angular cross section along its length and having one portion between said horns thinner than another and of greater flexibility than said horns.

2. A ring traveler comprising horns, a shank portion connecting said horns, said traveler having substantially the same amount of metal at any right angular cross section along its length and having a series of spaced portions between said horns thinner and of greater flexibility than said horns.

3. A ring traveler comprising horns, a shank portion connecting said horns, said traveler having substantially the same amount of metal at any right angular cross section along its length and having a series of portions between said horns thinner in cross section to provide a greater flexibility than said horns.

4. A ring traveler comprising horns, a shank portion connecting said horns and having at least one of its edges convexly curved outwardly to assist in discharging fibers tending to accumulate thereon.

5. A ring traveler comprising horns, a shank portion connecting said horns and having its opposite edges convexly curved outwardly to assist in discharging fibers tending to accumulate thereon.

6. A ring traveler comprising horns, a shank portion connecting said horns and having its opposite edges wider and thinner at one point than another between said horns.

7. A ring traveler comprising horns, a shank portion connecting said horns and having its edges wider and thinner than said horns at a series of spaced points between said horns.

8. A ring traveler comprising horns, a shank portion connecting said horns, said shank having substantially the same amount of metal at any right angular cross section along its length and having one portion between said horns of greater flexibility than said horns and having its edge convexly curved outwardly to assist in discharging fibers tending to accumulate thereon.

9. A ring traveler comprising horns, a shank portion connecting said horns and having its opposite edges wider and thinner than said horns at a point between said horns and also more flexible or resilient at said wider portion.

10. A ring traveler comprising horns, a shank portion connecting said horns and having its opposite edges wider at one point than another between said horns and also thinner at said widened portion.

11. A ring traveler comprising horns, a shank portion connecting said horns and having an inner and outer curved surface one of which is of a continuous curvature and the other of which

is an irregular curvature to vary the thickness and form one portion thinner than another, said thinner portion being also wider than the adjacent narrower portion, said shank being more flexible at said thinner portion.

12. A ring traveler comprising horns, a shank portion connecting said horns, said traveler having substantially the same amount of metal at any right angular cross section along its length and having one portion between said horns thinner and of greater flexibility than said horns and of a width greater than the shank to assist in preventing loading.

JAMES McD. McLEOD.
